UNITED STATES PATENT OFFICE

EDWIN P. BENSON, OF NEW YORK, N. Y.

DESIGN FOR PAPER TO BE USED FOR BANK CHECKS OR FOR LIKE PURPOSES

Application filed June 7, 1930. Serial No. 35,964. Term of patent 3½ years.

To all whom it may concern:

Be it known that I, EDWIN P. BENSON, a citizen of the United States of America, and resident of New York, county and State of New York, have invented a certain new, original, and ornamental Design for Paper to be Used for Bank Checks or for like Purposes, of which the following is a specification, reference being had to the accompanying drawing, forming part thereof.

In the drawing:

The figure is a plan view of a piece of paper, to be used for bank checks or for like purposes, showing my new design.

I claim:

The ornamental design for paper to be used for bank checks or for like purposes, as shown.

EDWIN P. BENSON.
